UNITED STATES PATENT OFFICE.

WILLIAM REAVELL AND EDWIN WALTER JONES, OF IPSWICH, ENGLAND, ASSIGNORS
TO THEMSELVES AND REAVELL & CO., LIMITED, OF IPSWICH, ENGLAND.

AIR-COMPRESSOR.

1,261,437.

Specification of Letters Patent. Patented Apr. 2, 1918.

Application filed June 24, 1916. Serial No. 105,757.

To all whom it may concern:

Be it known that we, WILLIAM REAVELL and EDWIN WALTER JONES, subjects of the King of Great Britain and Ireland, residing at Ipswich, in the county of Suffolk, England, have invented Improvements in Air-Compressors, of which the following is a specification.

This invention has reference to air compressors in which the compression is effected in three or more stages.

In some circumstances it is very desirable that the compressors should be compact especially as regards height; for instance in submarines, where there is little head room, ordinary types of compressors for the Diesel propelling engines are difficult to arrange in the space available.

Now, in constructing a compressor according to the present invention objects are to make it more compact and require less head room than ordinary types, to insure that it will be effectively balanced in working, and will have all its valves assembled in an accessible position.

For these purposes in an air compressor of the kind in which the high pressure stage of compression is effected in cylinders arranged parallel to and at opposite sides of the main cylinder and having their pistons connected to the main piston so as to reciprocate therewith, the high pressure pistons are connected to the main piston by a bridle piece or frame that is rigidly attached in any convenient way to the main piston below the center of the connecting rod crosshead or gudgeon and that is flexibly connected to the high pressure pistons by means which permit the said pistons to work properly in their cylinders even if there should be slight deflection in the bridle piece or frame under working conditions, or, if owing to faults in erection or other cause, perfect alinement should not be maintained; the high pressure cylinders are in free communication with a common chamber fitted with inlet and outlet valves so that the pressure on the high pressure pistons will be the same and "out of balance" conditions of pressure will be avoided; and the high pressure and intermediate pressure cylinders or spaces are connected to inlet and outlet valves situated with the low pressure valves at the top of the compressor by pipes or ports which constitute parts of

the high and intermediate compression spaces, the said cylinders or spaces being proportioned accordingly.

The accompanying drawings illustrate a three stage compressor embodying our improvements, Figures 1 and 2 being vertical sections taken at right angles to each other, Fig. 3 being a section on the line A A Fig. 1, Fig. 4 a plan of the head of the compressor with the cover removed and Fig. 5 a detail view illustrating one form of flexible connection between a high pressure piston and the bridle piece or frame; Fig. 6 is a similar view illustrating a modified form of such connection.

In this construction, the main cylinder *a* is of two diameters and is fitted with a trunk piston *b* reciprocated by a connecting rod *c*, the gudgeon pin of which is above the lower end of the piston, and a crank shaft *d* which may be an extension of the crank shaft of a Diesel engine; the first stage of compression is effected above the piston head and the second stage below the piston head in the annular space formed between the larger diameter of the cylinder and the smaller diameter of the trunk portion of the piston in the well known manner.

e, e are a pair of high pressure cylinders disposed at opposite sides of and parallel to the main cylinder *a*; the cylinders *e* may be attached independently to the top of the compressor standard as shown, or they may be integral with the main cylinder *a*. The cylinders *e* are fitted with pistons *f* that are flexibly connected to the arms of a bridle piece or frame *g* that is rigidly attached to the lower end of the trunk piston *b* as shown. In one method of connecting each piston *f* to its bridle arm, the lower end of the piston as shown in Fig. 5 is reduced and extends through a partly spherical washer *h* mounted in the enlarged and correspondingly shaped upper end of an opening in the bridle arm, the piston being tightly held in position but with sufficient freedom to take its true alinement in the cylinder by means of a coiled spring *i* compressed against the underside of the bridle arm by a nut *k*. In the arrangement shown in Fig. 6, the washer *h* is seated in a laterally movable carrier *h¹* instead of directly in the bridle arm and the carrier *h¹* is formed with a spigot *h²* which is of smaller

diameter than the opening in the bridle arm so that the carrier can move laterally in any direction; with this arrangement still greater freedom is given to the piston to take its true alignment.

All the valves are located in the casting *l* forming the main cylinder cover, the several valves being arranged as seen clearly in Fig. 4, *m* and *n* being the low pressure inlet and outlet valves respectively, *o* the intermediate pressure inlet valve to which air is led from the outlet valve *n* through the first stage intercooler (not shown) *p* the intermediate pressure outlet valve, *q* the high pressure inlet valve to which air is led from the valve *p* through the second stage intercooler (not shown); and *r* the high pressure outlet or delivery valve. The valves *o* and *p* control the passage of air to and from a chamber 20 that is in free communication with the bottom of the larger part of the cylinder *a* through a passage *s*, Figs. 2 and 4; and the valves *q* and *r* control the passage of air to and from a chamber (indicated by dotted 25 lines in Fig. 4) that is in free communication with both cylinders *e* through a bifurcated pipe connection *t*, Figs. 1, 2 and 4. The passage *s* and its connected valve chamber form part of the annular second stage 30 compression space and the pipe connection *t* and its connected valve chamber form part of the third stage compression spaces; so that the swept volume of these compression spaces has to be proportioned accordingly. 35 The cylinders *a* and *e* are contained in a cooling water jacket which is in communication with cooling water spaces in the casting *l* which is provided with a cover *u*.

What we claim is:—

40. 1. An air compressor comprising a main cylinder, a valveless trunk piston working therein, two high pressure cylinders arranged parallel to and at opposite sides of the main cylinder, pistons working in said cylinders, a connecting rod extending into and connected to the main piston, a bridle piece rigidly attached to the main piston below the connecting rod connection and carrying the high pressure pistons, substantially as described.

45. 2. An air compressor comprising a main cylinder, a piston working therein, two high pressure cylinders arranged parallel to and at opposite sides of the main cylinder, pistons working in said cylinders, a connecting rod connected to the main piston, a bridle piece rigidly attached to the main piston below the center of the connecting rod connection, and flexible connections between said bridle piece and the high pressure pistons adapted to permit said pistons to move in the bridle piece sufficiently to maintain alignment in their cylinders, substantially as described.

50. 3. An air compressor comprising a main

cylinder, a piston working therein, two high pressure cylinders arranged parallel to and at opposite sides of the main cylinder, pistons working in said cylinders, a fixed chamber in free communication with and common to both high pressure cylinders, an inlet valve to said chamber, and an outlet valve from said chamber, so that air passes both to and from said cylinders through said chamber and the pressure on the high pressure pistons will be the same, substantially as described. 70 75

4. An air compressor comprising a main cylinder, a valveless piston working therein, two high pressure chambers arranged parallel to and at opposite sides of the main cylinder, pistons working in said high pressure chambers, one intermediate pressure chamber, inlet and outlet valves for the main cylinder, inlet and outlet valves for the intermediate pressure chamber, one inlet valve and one outlet valve for the two high pressure cylinders, all the said valves being located in the top cover of the compressor, and connecting pipes or ports which constitute parts of the high and intermediate pressure chambers, the said chambers being proportioned accordingly. 80 85 90

5. An air compressor comprising a main cylinder, a piston working therein, two high pressure cylinders arranged parallel to and at opposite sides of the main cylinder, pistons working in said cylinders, a connecting rod connected to the main piston, a bridle piece or frame rigidly attached to the main piston below the center of the connecting rod connection, each high pressure piston having a reduced lower end, openings in the bridle arm through which the reduced ends of said pistons extend, a compressed coiled spring upon the extending ends of the pistons and nuts adapted to compress said springs and hold the pistons to the bridle piece or frame substantially as described. 95
100
105

6. An air compressor comprising a main cylinder, a piston working therein, two high pressure cylinders arranged parallel to and at opposite sides of the main cylinder, pistons working in said cylinders, a connecting rod connected to the main piston, a bridle piece or frame rigidly attached to the main piston below the center of the connecting rod connection, each high pressure piston having a reduced lower end, openings in the bridle arm through which the reduced ends of said pistons freely extend, spherical washers mounted at the mouth of said openings and adapted to support the pistons which extend therethrough, compressed coiled springs upon the extending ends of the pistons and nuts adapted to compress said springs and flexibly hold the pistons to the bridle piece, substantially as described. 110 115 120 125

7. An air compressor comprising a main cylinder, a piston working therein, two high 130

pressure cylinders arranged parallel to and at opposite sides of the main cylinder, pistons working in said cylinders, a connecting rod connected to the main piston, a bridle piece or frame rigidly attached to the main piston below the center of the connecting rod connection, each high pressure piston having a reduced lower end, openings in the bridle arm through which the reduced ends 10 of said pistons freely extend, laterally movable carriers mounted at the mouths of said openings, spherical washers mounted in said carriers and adapted to support the pistons which extend therethrough, compressed coiled springs upon the extending ends of 15 the pistons and nuts adapted to compress said springs and flexibly hold the pistons to the bridle piece, substantially as described.

Signed at Ipswich, in the county of Suffolk, England, this twenty-sixth day of May, 20 1916.
